REFRIGERATOR CAR CONSTRUCTION

Kurt E. Zeidler, Pittsburgh, Pa., assignor to
Standard Railway Refrigerator Company, Chi-
cago, Ill., a corporation of Delaware

Application October 13, 1938, Serial No. 234,807

5 Claims. (Cl. 62—17)

This invention relates to refrigerator cars used to transport perishable commodities at a pre-determined temperature. The essential features of such a car are an insulated structure, and a cooling means for use in warm weather or a heating means for use in cold weather.

The invention relates particularly to cars of the overhead bunker type in which refrigerant containers are suspended immediately below the roof. A common type of overhead bunker car has enclosures around the containers to form refrigerant compartments, said compartments having openings near the tops thereof for the entrance of warm air and near the bottom thereof for the discharge of cooled air. The cooled air flows downwardly through vertical flues which communicate with said discharge openings, the cooled air flowing to a space under the floor rack from which it may circulate upwardly through the lading.

The object of this invention is to provide a light, strong refrigerant container which, to a certain extent, forms its own supporting means. Since the refrigerant containers in a car of this type are near the top of the car, it is important that the containers be as light as possible so as not to raise the center of gravity of the car unnecessarily. But the large weight of ice which shifts in the containers during service movements of the car requires that the containers be strong. To meet these severe requirements of great strength and light weight, I have invented a construction wherein some of the container walls function as beams supported by the car structure. The other walls and the bottom of the container are supported by said beams, thus eliminating the necessity of having an additional truss or other means to support the containers.

Another object of the invention is to use the roof and walls of the car to support the containers and to insulate the containers from the exterior of the car so as not to impair the insulation efficiency thereof. It is a further object of the invention to provide means of support which are readily accessible so that the containers may be easily removed for service and repair work.

Other advantages of my invention will be apparent from the following detailed description by referring to the drawings.

Fig. 1 is a partial transverse section of a refrigerator car, the left half being on line 1L—1L and the right half on line 1R—1R of Fig. 2. The insulation has been omitted for clarity.

Fig. 2 is a longitudinal section on line 2—2 of Fig. 1.

Fig. 3 is a plan view of the structure shown in Figs. 1 and 2, the roof and side wall insulation having been omitted.

The parts of the refrigerator car shown in Fig. 1 are side plates 2, side sheathing 3, side lining 4, ceiling 5, roof 6, running board 7, hatch frame 8 surrounding the hatch 9, refrigerant containers 10, drip pans 11 and false walls 12 which provide the flues 13 for flow of air and melted refrigerant to the lower part of the car.

The side 20 of a refrigerant container 10 nearest the center of the car is shown constructed of an upper chord 21 and a lower chord 22 connected by struts 23. The diagonal braces 24 are positioned so that the side 20 functions as a truss supported at two points, namely, the brackets 25. Angle clips 26 are shown to connect the upper chord 21 to the brackets 25. The side 20 of the container 10 is then a simple beam suspended between the brackets 25 and having a cantilever beam projecting from each end thereof.

The roof 6 preferably comprises a plurality of sheets 30 extending transversely of the car between the side plates 2 and having upstanding flanges 31 at the edges thereof. Seam caps 32 which overlie the flanges 31 and are secured thereto also extend between the side plates 2 and partially support the roof. Saddles 33 are secured to the seam caps 32 and support the running board 7. Vertically disposed plates 34 having horizontal flanges 35 are positioned between some of the flanges 31 and attached preferably by rivets 37 which secured the flanges 31 to the seam caps 32. Wooden blocks 36 rest upon the flanges 35 and are secured to the plates 34 by horizontal bolts 38. The brackets 25 are suspended from the blocks 36 by the vertically disposed bolts 39, bolts 38 being arranged in staggered relation to the bolts 39 to insulate the brackets 25 from the roof 6.

The side 50 of the container 10 nearest the side wall comprises an upper chord 51, a lower chord 52 and spaced apart vertical connecting members 53, preferably Z shaped members. Insulating pieces 54, preferably wood stringers, may be secured to the vertical frame members 55. Bolts 56 through the members 53 and the pieces 54 rigidly secure the side 50 of the container to the side wall of the car. The side 50, therefore, functions as a beam supported by the several spaced apart members 53.

The bottom of the container consists of a plurality of inverted channel shaped members 60 supported by the lower chords 22 and 52 of the

sides 20 and 50. The ends 61 of the container are also supported by the sides 20 and 50.

Although the side 50 is shown supported from the side wall of the car, it could also be supported from the roof in the manner shown for side 20 if desired. It is intended that this construction be considered part of my invention.

The refrigerant containers 10 are shown with foraminous sides and bottom. The invention should not be limited to this construction but includes containers having the lower part imperforate and also containers having all walls imperforate for the retention of a liquid refrigerant or dry ice.

It should not be construed that my invention is limited to containers having the walls formed of trusses. For example, the construction shown could be adapted to containers having their walls functioning as girders. I claim as my invention any construction in which the walls of the containers are beams supported at spaced apart positions.

The accompanying drawings illustrate the preferred form of the invention, though it is to be understood that the invention is not limited to the exact details of construction shown and described, as it is obvious that various modifications thereof, within the scope of the claims will occur to persons skilled in the art.

I claim:

1. In a refrigerator car having a roof comprised of metallic outer sheets and insulating lining, a metallic member depending from said sheets and disposed entirely in the space between said outer sheets and said lining, an insulating piece attached to said metallic member, pliable insulation in said space, a refrigerant container below said lining, and means extending through said lining to attach said container to said insulating piece.

2. In a refrigerator car having a wall and a roof, a refrigerant container below said roof and adjacent said wall in spaced relation thereto, spaced apart members extending between and secured to said wall and the side of the container adjacent thereto, spaced apart brackets depending from said roof and secured to the opposite side of said container, the end of said container extending between and secured to said sides, said sides functioning as beams supported by said members and said brackets, said container being

constructed and arranged so that said beams form the sole support for the container and the contents thereof.

3. In a refrigerator car having a wall and a roof, a refrigerant container below said roof and adjacent said wall in spaced relation thereto, spaced apart members disposed remote from the ends of said container extending between and secured to said wall and the side of the container adjacent thereto and spaced apart brackets depending from said roof and secured to the opposite side of said container remote from the ends thereof, the ends of said container extending between and secured to said sides, said sides functioning as beams supported by said members and said brackets, said container being constructed and arranged so that said beams form the sole support for the container and the contents thereof.

4. In a refrigerator car having a wall and a roof, a refrigerant container below said roof and adjacent said wall in spaced relation thereto, spaced apart members extending between and secured to said wall and the side of the container adjacent thereto, means to direct a flow of air in contact with said container, said container being arranged so that some of said air flows through the space between said wall and said side and spaced apart brackets depending from said roof and secured to the opposite side of said container, the ends of said container extending between and secured to said sides, said sides functioning as beams supported by said members and said brackets, said container being constructed and arranged so that said beams form the sole support for the container and the contents thereof.

5. In a refrigerator car having a roof and a wall, a refrigerant container below said roof and adjacent said wall in spaced relation thereto, the side of said container adjacent said wall comprising spaced apart substantially horizontal upper and lower chords, spaced apart connecting members extending between said chords, and foraminous sheeting secured to said chords and connecting members, certain of said connecting members being secured to said wall so that said side functions as a beam arranged to support said container and the contents thereof.
